UNITED STATES PATENT OFFICE.

ROBERT L. PEARSON, OF CHESTERVILLE, MARYLAND.

CORN-HARVESTER.

SPECIFICATION forming part of Letters Patent No. 389,004, dated September 4, 1888.

Application filed November 29, 1887. Serial No. 256,461. (No model.)

To all whom it may concern:

Be it known that I, ROBERT L. PEARSON, a citizen of the United States, residing at Ches-
terville, in the county of Kent and State of
Maryland, have invented certain new and use-
ful Improvements in Corn-Harvesters; and I
do declare the following to be a full, clear,
and exact description of the invention, such
as will enable others skilled in the art to
which it appertains to make and use the same,
reference being had to the accompanying
drawings, and to the letters and figures of
reference marked thereon, which form a part
of this specification.

This invention relates to harvesting-ma-
chines which are chiefly designed for har-
vesting corn, cane, and kindred growth hav-
ing a thick stalk and which attains a great
height.

The object of the invention is the produc-
tion of a machine which will be light-running
and which will perform its work in an effi-
cient and satisfactory manner, and which will
carry the harvest and drop it in a heap at the
will of the driver.

The essential feature of the improvement
consists in having the machine provided with
guards which give direction to the stalks and
prevent injury to the conveyers which grasp
the stalks and carry them from the front end
of the machine to the rear end and deposit
them in a pile until such time as it may be de-
sired to deposit them on the ground in a heap
or shock. The carrier on which the load
rests is set in motion by the driver operating
a shipper-lever, and quickly ejects the load.
The gathering-arms are of novel pattern and
disposed equally above and below the con-
veyer-chains to distribute the strain equally
on the upper and lower edges of the said
chains. They are preferably arranged in
pairs, and the arms of each pair are located
opposite each other.

The improvements consist in the peculiar
construction and combination of parts, which
will more fully hereinafter appear and be
claimed, reference being had to the accom-
panying drawings, in which—

Figure 1 is a plan view, parts being broken
away, of a harvesting-machine of my con-
struction embodying my invention; Fig. 2, a
section on the line X X of Fig. 1, looking

in the direction of the arrow; Fig. 3, a side
view, parts being broken away, of the ma-
chine; Fig. 4, a longitudinal section on the line 55
Y Y of Fig. 1; Fig. 5, a detail view, parts be-
ing broken away, of the carrier; Fig. 6, a view
of one part of the guard, showing the side
provided with the guideway; Fig. 7, a detail
view of the conveyer-links having the studs 60
which support the gathering-arms, on an en-
larged scale; Fig. 8, a plan view of a gather-
ing-arm on an enlarged scale; Fig. 9, a front
view of a gathering-arm, and Fig. 10 a cross-
section on the line Z Z of Fig. 1 through the 65
guard and conveyer-chain. Fig. 11 is a cross-
section of the slotted arm F', showing the
means for adjustably connecting the sprocket-
wheel G² thereon; Fig. 12, a detail view of the
block e² and the means for connecting it ad- 70
justably with the beam or sill of the machine;
Fig. 13, a cross-section of the lower portion of
the harvester-platform on the line 13 13 of
Fig. 1, on an enlarged scale, showing the man-
ner of supporting the platform; and Fig. 14, a 75
cross-section on the line v v of Fig. 12.

The frame of the machine, composed of the
front sill, A, the rear sill, A', the side beams
A² and A³, the longitudinal beams A¹⁰ A⁴, par-
allel with each other and with the side beams, 80
the standards A⁵, the upper beams A⁶, A⁷, and
A⁸, and suitable cross bars, A⁹, between the up-
per beams A⁶ and A⁷, is supported on two
wheels, C and C', and is drawn forward by
draft being applied to the tongue a, which 85
is hinged to the cross-bar a', secured to beams
A² and A⁴. The tongue is braced by the stay
a², and is adjusted by the lever a³, which is
connected with the tongue by the rod a⁴. The
purpose of adjusting the tongue is to regu- 90
late the height of the front sill of the frame
from the ground to gage the length of stalk
to be left standing after the harvest is reaped.
The beams A³ and A⁴ are extended forward
from the sill A, and the ends are beveled on 95
the inner and lower sides. The lower sides
are beveled to permit the beams A³ and A⁴
to run close to the ground, and the inner
sides are beveled to permit the stalks to more
readily enter in between the beams A³ and 100
A⁴. The sides B, extending from the lower
beams A³ and A⁴ to corresponding upper
beams, A⁸ and A⁶, form a trough, in which
the stalks are gathered and retained until a

sufficient quantity to form a shock is collected, when, through mechanism presently to be described, it is deposited in a heap. This trough is closed by the bottom B' , above which is arranged the platform B^2 , supported in any suitable manner between the sides B , preferably on the transverse bars B^4 , and having tracks b at each edge, on which travel the endless carrier B^3 , composed of chains D and slats or bars D' . The sides of the said trough project in front of the sill A , being extended by the auxiliary side pieces, B^5 , which have their front ends inclining from the front ends of their respective upper beams to the front ends of the corresponding lower beams. The carrier-chains pass over pulleys E and E' , located at opposite ends of the platform B^2 , and each alternate link has a lateral projection, d , which receives the ends of the slats or bars D' , which are journaled thereon. The ends of the slats or bars are round, and this round portion d' is adapted to travel on the tracks b . The lower part of the carrier travels in the space between the bottom B' and platform B^2 . The bottom B' keeps the carrier from coming in contact with the ground and the standing stubble. The platform B^2 forms a bearing for the carrier on which the cut stalks lie, and also prevents the ears of corn from interfering with the motion of the slats or bars D' , which they would do were this platform not provided. The pulleys E are in the form of sprocket-wheels, and are keyed to the shaft e , located in front of and directly below the end of the platform B^2 , and journaled in bearings in the beams A^3 , A^4 , and A^{10} .

The pulleys E' are journaled loosely on the arms e' , projecting laterally from the blocks e^2 , placed on the rear ends of the beams A^3 and A^4 , and held adjustably thereon by the set-screws e^3 , extending through slots e^4 in the blocks. These blocks e^2 are held from turning about on the set-screws e^3 by having tongues e^5 projecting from their under sides, which enter the grooves e^6 in the top of the said beams A^3 and A^4 . In case the carrier becomes slack the blocks are adjusted to take up the slack and tighten the carrier, which is accomplished by loosening the set-screws e^3 , moving the blocks rearward, and retightening the said screws e^3 .

The guards F , two in number, arranged directly over the platform and carrier, and extending out in front beyond the carrier and cutter, have their middle portions approaching very close to each other to form a narrow passage-way, through which the stalks are carried from the front to the rear end of the platform, and have their ends oppositely flared, in order that the conveyers, which run in ways therein, may more easily gather in the standing stalks and convey them to a proper position to be cut, and more readily relinquish them when desired. These guards are supported at their ends on standards projecting up from the top beams A^6 and A^8 and intermediate of the ends by the three brackets F' , which are

secured at their inner ends, in any suitable manner, to the upper side beams A^6 A^8 , respectively. The conveyers G grasp the stalks and carry them to the rear end of the machine and deposit them on the carrier B^3 . The conveyers are, in this instance endless chains provided with gathering-arm g , and pass around the sprocket-wheels G' at each end of the guards, the sprocket-wheels G^2 at the points of flection or the guards, and the sprocket-wheels G^3 , adjustably held on the middle bracket of the brackets F' , to tighten the chains when through any cause they become slack. These conveyers G may be arranged at any level relative to the guards, which prevent them from being crowded by the stalks; but preferably are so disposed that a portion of the guard is above and another portion below them to brace the conveyer in all directions and prevent it from torsional strain. The guards are each composed of two rails, which embrace the conveyers and are held separated by short posts, on which the sprocket-wheels G' and G^3 are mounted.

The gathering-arms g are pivoted near their inner ends on studs g' , projecting from the links of the conveyer-chains, and have flanges g^2 , which travel in ways on the opposing sides of the rails of the guards to hold them stiff when gathering in the stalks and conveying them through the narrow passage between the guards.

In order to have the strain distributed equally on the conveyer-chains, it has been found expedient to provide the gathering-arms in pairs and locate one gathering-arm of each pair directly above the other or corresponding arm, and to have the arms attached to opposite edges of the same link, as shown. The guideways are grooves formed on the opposing sides of the rails of the guards and flare at their entrance ends to permit the flanges to freely enter therein. The inner corners of the flanges are beveled, so that their edges which enter the grooves will be sharpened to a chisel edge, thereby preventing the ends of the flanges catching on the ends of the guards on either side of the guideways, which only extend from the front ends of the guards to the rear point of flection. The rails of the guard may be flanged or provided with strips at each edge, between which a space is left to form the guideways.

The cutter H , arranged in front of the carrier B^3 and working on the front sill, A , is protected by the guards h , which are rounded on their front ends to prevent them striking into the stalks, but push them to the right or left, so that they will be directed to the cutter between the guards to be cut. The guards hold the standing stalks rigidly in place while being cut. The cutter is connected by pitman h' with the crank h^2 on the end of the main shaft I , which is journaled parallel with the side beams and at right angles to the shaft e , with which it is geared by the miter or bevel gear-wheels i and i' . The shaft J , journaled

parallel with the shaft *e* on the beams *A*³, *A*⁴, and *A*¹⁰, near the rear end of the machine, is driven from shaft *I* by the bevel gear-wheels *l*² and *l*³, and is provided with bevel gear-wheels *j*, which mesh with corresponding bevel gear-wheels *k*, on the vertical shafts *K*, to the upper ends of which the rear sprocket-wheels, *G*, are keyed. The shaft *L*, mounted in bearings on the beam *A*¹⁰, has the pinion *l* on its inner end and the bevel gear-wheel *l*' on its outer end. The pinion *l* meshes with the gear-wheel *C*, keyed to the side of the drive-wheel *C*. The bevel gear-wheel *l*' is in mesh with the pinion *l*³ on the shaft *I*. A half-clutch, *l*⁴, extends from the rear of the pinion *l*³ to mesh with a corresponding half-clutch, *l*⁵, mounted on the shaft *I*. The half-clutch *l*⁴ is adapted to move longitudinally on the shaft to and from the half-clutch *l*⁵, and is keyed to revolve with the shaft, and is held in engagement with the half-clutch *l*⁵ by the coil-spring *M*, placed on shaft *I*. The hand-lever *m* for moving the half-clutch *l*⁴ extends within convenient reach of the driver's seat *N*, which is mounted on a board, *N'*, secured to the cross-bars *A*⁹.

The bevel gear-wheel *i* is loosely mounted on shaft *I*, and from its rear the half-clutch *n* extends and is engaged by the half-clutch *n'*, keyed to revolve with but free to have a longitudinal movement on shaft *I*. The half-clutch *n'* is in engagement with the shipper-lever *O*, and is normally held out of engagement with *n* by the spring *n*², interposed between the upper end of the lever *O* and board *N'*. The foot-lever *P*, located within convenient reach of the driver's foot, is connected with the shipper-lever *O* to be operated at will to bring the half-clutches *n* and *n'* together for operating shaft *e* and the carrier *B*² for discharging the load. The guard-bar *Q* prevents the wheel *C* crushing any grain and forcing it into the earth, while the guard-rail *R* prevents the conveyer on the side with wheel *C'* from catching in the tops of the blades or stalks.

In practice the machine is drawn forward so that the line of stalks will come between the sides *B*, being assisted by the conveyers *G*. The stalks, when cut, are carried to the rear end of the machine and deposited in a pile on the carrier by the conveyers. When a sufficient quantity has accumulated, the driver presses on the foot-lever and throws the carrier in gear, which quickly deposits the load in a heap. The carrier is thrown out of gear by the shipper-lever *O*. The wheels *C* and *C'* are disposed so that the frame is nearly balanced thereon and is a trifle heavier in front, so as not to be overbalanced when loaded. The gathering-arms are held rigid when traveling from the front ends of the guards to the rear point of flexion of the guards, at which point their flanged ends leave the guideways and they drop their burden.

Having thus described my invention, what I claim, and desire to secure by Letters Patent, is—

1. The combination, with the guards having their front and their rear ends flared or oppositely inclined, and having their middle portions approaching close to and parallel with each other, as shown, of the sprocket-wheels *G*' and *G*², located at the ends of the inclined portions of the guards, and the conveyers adapted to follow the path of the guards in their travel from the front to the rear of the machine and passing around said sprocket-wheels, substantially as and for the purpose described. 70

2. In a harvesting-machine, the combination, with the frame, the sides *B*, forming a trough, the endless carrier located at the bottom of the trough, and means, substantially as described, for operating the said carrier, of the guards having their ends flared and having their middle portions brought close together to form a narrow passage between the guards, which passage is above the said carrier, and the conveyers following the line of the guards, substantially as described. 80 85

3. The combination, with the guard having a groove, which groove flares at its entrance end, of the conveyer-chain and the gathering-arms provided with flanges which have their front ends beveled, substantially as and for the purpose described. 90 95

4. The combination, in a harvesting-machine, of the guard composed of two rails, one rail being arranged above the other rail and each rail having a guideway in its opposing side, the conveyer-chain having some of its links provided with studs, which extend from the opposite edges of the links, and the gathering-arms arranged in pairs and mounted on the studs of the links, and having flanges 105 which engage the said guideways, substantially as described.

5. In a harvesting-machine, the combination of the frame, the sides *B*, forming a trough, the bottom *B*², the platform *B*², arranged above the bottom and having a track at each edge, the carrier-chains passing around the platform *B*², and the slats or bars journaled at their ends to the carrier-chains and having their ends rounded and adapted to travel on the tracks, substantially as described. 110 115

6. In a harvesting-machine, the combination of the frame, the sides *B*, the endless carrier, the blocks *e*², fitted to the frame by a tongue-and-groove joint and having slots, the set-screws *e*³, passing through the slots into the frame for adjustably holding the blocks on the frame, the arms *e*', projecting from the blocks, and the pulleys mounted on the arms and supporting the rear end of the carrier, substantially as described. 120 125

In testimony whereof I affix my signature in presence of two witnesses.

ROBT. L. PEARSON.
